[57] CLAIM

The ornamental design for a speaker box, as shown and described.

DESCRIPTION

FIG. 1 is a perspective view of a first embodiment of a speaker box showing my new design;

FIG. 2 is a top plan view thereof;

FIG. 3 is a left side elevational view thereof;

FIG. 4 is a front elevational view thereof;

FIG. 5 is a bottom plan view thereof;

FIG. 6 is a right side elevational view thereof;

FIG. 7 is a rear elevational view thereof;

FIG. 8 is a reference perspective view thereof wherein a stand is attached thereto;

FIG. 9 is a reference front view thereof wherein the speaker box is attached to a monitor;

FIG. 10 is a perspective view of a second embodiment of a speaker box showing my new design;

FIG. 11 is a top plan view of the embodiment of FIG. 10;

FIG. 12 is a left side elevational view of the embodiment of FIG. 10;

FIG. 13 is a front elevational view of the embodiment of FIG. 10;

FIG. 14 is a bottom plan view of the embodiment of FIG. 10;

FIG. 15 is a right side elevational view of the embodiment of FIG. 10;

FIG. 16 is a rear elevational view of the embodiment of FIG. 10;

FIG. 17 is a reference perspective view of the embodiment of FIG. 10 wherein a stand is attached to the speaker box; and,

FIG. 18 is a reference perspective view of the embodiment of FIG. 10 wherein the speaker box is attached to a monitor;

FIG. 19 is a front elevational view of a third embodiment of a speaker box showing my new design;

FIG. 20 is a reference perspective view of the embodiment of FIG. 19 wherein the speaker box is attached to a monitor; The remaining views of the third embodiment are mirror images of the respective views of the first embodiment;

FIG. 21 is a front elevational view of a fourth embodiment of a speaker box showing my new design;

FIG. 22 is a reference perspective view of the embodiment of FIG. 21 wherein the speaker box is attached to a monitor; and,

The remaining views of the fourth embodiment are mirror images of the respective views of the second embodiment. The broken line showing of the stand on FIGS. 8 and 17 and the monitor portions on FIGS. 9, 18, 20 and 22 are for illustrative purposes only and form no part of the claimed design.
